SOLE REST FOR PULLING-OVER MACHINES

Robert P. Frye, Marlboro, Mass.

Application January 12, 1933. Serial No. 651,272

1 Claim. (Cl. 12—4)

This invention relates to pulling-over machines used in preparing shoes for lasting by performing the operation of pulling the upper over upon a last and an inner sole of a shoe when the shoe parts are assembled on the last, and particularly to a machine which includes pulling-over mechanism organized as shown by the McFeely Patent No. 1,029,387, granted June 11, 1912.

The McFeely machine includes a shoe bottom rest called a sole rest, adapted to position the inner sole on the last with its toe end flush with the toe end of the last, the rest being movable to move the inner sole forwardly and backwardly on the last, and the shoe being presented bottom upward to the sole rest and supported thereby while the upper is being pulled about the last.

A function of the sole rest is to conform the fore part of the inner sole to the fore part of the last bottom. All portions of the margin of the inner sole fore part should be in close contact with the last bottom in order that there may be no gap between the inner sole and the last bottom when the upper is being pulled over by the usual wipers. A gap at any point causes liability of displacement of portions of the upper lining in the form of folds or puckers which project between the inner sole and the last bottom and remain there in the completed shoe, thus constituting an imperfection in the shoe. Moreover, if the portions of the inner sole edge are separated by gaps from the last bottom, such portions are liable to be distorted by pressure of the side wipers against them, so that burrs are formed on the sole edge constituting another imperfection.

The construction of the McFeely sole rest is such that the completed shoe is liable to have the above mentioned imperfections.

The object of my invention is to so improve the sole rest as to prevent any liability of imperfections caused as above stated.

Of the accompanying drawing forming a part of this specification,—

Figure 1 is a longitudinal section through the sole rest mechanism of a pulling-over machine showing my improved sole rest, the mechanism being otherwise as shown by the McFeely patent.

Figure 2 shows in perspective my improved sole rest.

Figure 3 is a section on line 3—3 of Figure 1.

Figure 4 is a section on line 4—4 of Figure 3.

Figure 5 is an enlargement of Figure 4 showing the grippers.

Figures 6 and 7 are views similar to Figures 1 and 3 showing the sole rest of the McFeely patent.

Figure 8 is a section on line 8—8 of Figure 7. The same reference characters indicate the same parts in all of the figures.

The sole rest hereinafter described is associated, as described by the McFeely patent, with means for pulling an upper over a last, and means for actuating the sole rest to move the inner sole with relation to the last, the general operation of the sole rest being as fully set forth by said patent.

To facilitate an understanding of the nature and object of my invention, I will first describe the sole rest of the McFeely patent.

The sole rest is mounted slidingly in a carrier 120 which is pivotally supported. The sole rest comprises a shank 118, having two arms 124 which extend obliquely forward from the shank to engage the rear portion of the fore part of the inner sole S near its opposite edges, and an arm 126 which extends directly forward toward the toe of the inner sole, as shown by Figure 7. The arm 126 has an adjustable foot piece 127 pivoted to it at 128, and acted on by a spring-pressed plunger 130. The foot piece is provided with a stop screw 132 for adjusting it about its pivot to vary the vertical position of the acting end of the foot piece with relation to the arm 126, so that the sole rest may be adapted to properly engage lasts, the bottom faces of which have different degrees of curvature.

The adjustable foot piece 127 projects forward from the arm 126, and its forward end engages the toe portion of the inner sole S only on the longitudinal median line thereof as indicated by Figure 7, so that the foot piece 127 does not engage the toe portion of the inner sole in such manner as to press the entire edge of the toe portion against the curved bottom of the last. In other words, the median line of the toe portion contacts with the sole bottom, and the edges of the toe portion at opposite sides of the median line stand out from the last bottom so that the gaps shown by Figure 8 are formed.

The mechanism shown by the McFeely patent for wiping and pressing the pulled upper into position to receive tacks securing the upper to the inner sole and last includes wipers 60^a which are movable to wipe the edge of the upper over upon the outer side of the inner sole and are adapted to exert pressure on the wiped over edge and hold it from slipping back after it is released by the grippers 186. Two of the wipers 60^a are shown by Figure 4, and one by Figure 8, the wipers being shown in their outward position before they are actuated to perform their func-

tion. These wipers are movable crosswise of the last, and are called the lateral wipers.

After the lateral gripper carriers 161 (Figure 5), are actuated to cause the grippers 186 to pull over the upper, the lateral wipers 60^a are actuated inwardly to hold the upper preparatory to tacking the upper to the insole and last.

By reference to Figure 8 it will be seen that when there are gaps between the inner sole edge and the last bottom, the lateral wipers 60^a in moving inwardly from the position shown to perform this function, are liable to press the edge of the upper inwardly against the edge portions of the inner sole which stand out from the last bottom, before said edge portions are forced downwardly against the last bottom by the actuation of the lateral wipers. The edges of the inner sole are therefore liable while they are being forced downwardly, to displace portions of the upper lining in such manner as to cause wrinkles or puckers on the lining which project into the gaps between the inner sole and the last bottom, and are pinched and permanently retained therein when the gaps are closed, thereby causing an objectionable defect.

It sometimes happens that when the margin of the toe portion of the inner sole stands out from the last bottom the lateral wipers 60^a exert pressure on the edge of the standing out portion of the sole edge, said edge being usually relatively thin and known as the "insole feather". Such pressure tends to crush the innersole edge and form burrs thereon which cause irregularities on the outer side of the upper which are noticeable in the completed shoe, and constitute another defect.

In carrying out my invention I substitute for the adjustable foot piece 127, the foot piece shown by Figures 1, 2, 3, 4, and 5. This foot piece includes a shank 12 pivoted at 13 to the arm 126,

and in alignment with the shank 118, and two arms 14 projecting laterally from the shank and arranged to bear on the margin of the toe portion of the inner sole S at opposite sides of the longitudinal median line of the sole, as indicated by Figures 3. The arms 14 may project obliquely forward as shown by Figures 2 and 3, or they may be in line with each other and project laterally without projecting obliquely forward, the shank 12 and arms 14 forming a T-shaped body. The foot piece formed by the shank 12 and arms 14 is adjustable, like the foot piece 127, about the pivot 13 to vary the vertical position of the acting ends of the arms with relation to the arm 126. The feet, or acting portions of the arms 14, are preferably formed by flanges 16 formed and arranged to bear on the margin of the toe portion of the inner sole and press said margin against the last bottom, as indicated by Figure 4, so that no portions of said margin stand out from the last bottom, and there is no liability of pinching portions of the lining between the inner sole and the last bottom, and of crushing the margin of the toe portion of the inner sole by the lateral wipers 60^a.

The wiper 60^a shown by Figure 1 is movable lengthwise of the last, and is not a lateral wiper, its function being to act on the middle of the toe portion of the upper.

I claim:

A pulling-over machine sole rest including laterally extending arms for engaging the rear portion of an inner sole fore part near its opposite edges, and a forwardly extending arm, said rest being characterized by a foot piece, adjustably connected with said arm, and having laterally extending arms for engaging the toe portion of said fore part at opposite sides of the longitudinal median line of the inner sole.
